Primary Examiner—Antoine D. Davis

(57) **CLAIM**

The ornamental design for hand-held unit of an electronic thermometer, as shown and described.

DESCRIPTION

FIG. 1 is a front perspective view of a hand-held unit of an electronic thermometer showing a probe and cord of the electronic thermometer in phantom;

FIG. 2 is a front elevational view of the hand-held unit of an electronic thermometer with the probe and cord removed for clarity of illustration;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The probe and cord shown in phantom in FIG. 1 form no part of the design.
